(57) **CLAIM**

The ornamental design for a cranial implant, as shown and described.

DESCRIPTION

FIG. 1 is top-rear-right perspective view of a first embodiment of a cranial implant, showing our design;

FIG. 2 is a top-front-left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top-rear-left view thereof;

FIG. 10 is a bottom-rear-right view thereof;

FIG. 11 is a bottom-rear-left view thereof;

FIG. 12 is top-rear-right perspective view of a second embodiment of the cranial implant;

FIG. 13 is a top-front-left perspective view thereof;

FIG. 14 is a front view thereof;

FIG. 15 is a rear view thereof;

FIG. 16 is a left side view thereof;

FIG. 17 is a right side view thereof;

FIG. 18 is a top view thereof;

FIG. 19 is a bottom view thereof;

FIG. 20 is a top-rear-left view thereof;

FIG. 21 is a bottom-rear-right view thereof; and,

FIG. 22 is a bottom-rear-left view thereof.

The portions of the cranial implant that are de-emphasized in a low tonal contrast form no part of the claimed design. The broken line showing throughout the figures represents the boundary of the claim.
